UNITED STATES PATENT OFFICE.

JOHN D. MCPHERSON, OF HILLBURN, NEW YORK.

TONGUE-SWITCH.

1,085,870.

Specification of Letters Patent.

Patented Feb. 3, 1914.

Application filed January 22, 1913. Serial No. 743,494.

To all whom it may concern:

Be it known that I, JOHN D. MCPHERSON, a citizen of the United States, residing at Hillburn, in the county of Rockland, in the State 5 of New York, have invented certain new and useful Improvements in Tongue-Switches, of which the following is a specification, reference being had to the accompanying drawings, forming a part hereof.

10 My invention relates to improvements in switches, which are adapted for use in connection with railways, and which are subject to the heavy loads and the high speeds of railway trains and the invention consists in 15 the new and novel features of construction and combinations of parts hereinafter set forth and claimed.

One of the objects of my invention is to 20 provide a tongue switch in which the tongue is securely held in proper position with relation to the switch block by means which will permit the tongue to be readily assembled or removed for replacement or repairs.

25 A further object of the invention is to provide a secure bearing between the tongue and the switch block, so that tilting or accidental displacement of the tongue may be prevented.

30 A further object of the invention is to provide means whereby wear between the bearing parts of the tongue and switch block will be automatically compensated without manual adjustment of the parts.

35 The various other objects of the invention will be set forth in connection with the following description of one form of tongue switch embodying my invention, which is illustrated in the accompanying drawings, in which:—

40 Figure 1 represents a plan view of a tongue switch embodying my invention, together with means for adjusting and holding the tongue in position. Fig. 2 represents a plan view of the heel portion of the switch tongue. Fig. 3 represents a side elevation of the same. Fig. 4 represents an end view of the switch tongue. Fig. 5 represents a detail plan view of the heel portion of the switch, with the tongue and box or housing cover removed. Fig. 6 represents a longitudinal section on the lines $\alpha-\alpha$ of Fig. 5, with the tongue in place. Fig. 7 represents a transverse section on the lines $y-y$ of Fig. 5, with the tongue and box cover in place. Fig. 8 represents a detail longitudinal section on the lines $z-z$ of Fig. 5. Fig. 9 is a detail view of the forked end of the adjusting lever. Referring to the particular embodiment of the invention shown in the drawings, the track rails 1, 1^a, are secured to the heel portion of the switch block and the guard rails 2—2^a are also secured to the heel portion of the switch block, by suitable means, as the bolts 3. Filler blocks 4 are interposed between the track rails and guard rails which are grooved to provide flangeways in the usual manner.

45 The switch plate comprises a heel block 5, preferably formed integral therewith, which has a convex bearing face 6 that is undercut 60 as at 7 to form a socket and is also provided with lateral flanges 8 forming the floor of the flange way. Forwardly of the bearing face the switch plate is provided with a central recess 9 connected by a lateral 70 passage 10 that is provided in the switch plate and the adjacent guard rail with a box or housing 11 secured to the outside of said guard rail. The upper face of that portion 75 of the switch plate in front of the bearing face is approximately in the same horizontal plane as the floor of the socket 7 and provides a bearing for the switch tongue. Bearing sockets 12 are also formed beneath the lateral flanges 8 in connection with a bearing bar 13 which is secured underneath the 80 switch plate.

50 The tongue 14 has its heel portion concavely curved to register with the curved portion of the heel block and is provided 85 with a downwardly and rearwardly extending projection or extension 16 to engage in the undercut socket 7 formed in the heel block and bearing upon the flat bottom thereof. The tongue is also provided with 90 rearwardly and downwardly extending projections or fingers 17 formed from the crescent ends of the tongue heel that engage in the sockets or recesses 12. A downwardly 95 extending extension or arm 19 is also provided on the bottom of the tongue, approximately in the medial line thereof, which seats in the rear portion of the central recess 9, formed in the switch plate. Preferably 100 said arm is provided with a slightly convex front face 20 and is engaged by the correspondingly concaved end of a latch or plunger 21. Said plunger is movably 105 mounted in the recess 9, and is preferably made in two parts, movable with relation to 110

each other, which are provided with registering recesses 22 to receive a coiled spring 24. The forward end of said plunger rod is slotted as at 25 and provided with a pivot 5 pin 26. One arm 27 of a ball crank lever 28 that is fulcrumed on a pivot pin 29 mounted in the box or housing 11 is pivoted to the plunger 21. The other arm 30 of said lever is slotted as at 31, and engages with a 10 threaded bolt 32 having an eye through which a pin 33 passes, that is slidably mounted in slotted guides 34 formed in the wall of the box or housing. Locking nuts 35, or other adjustable securing means, are 15 provided on the end of the bolt whereby the bell crank lever 28 may be adjustably held in its proper position. The box or housing is provided with a removable cover 36 having a downwardly extending lug 37 provided with a socket 38 adapted to embrace 20 the hub of the bell crank lever and overlie the pivot pin 29 and hold the same in its seat.

The switch is assembled by securing the 25 parts in the position shown in Fig. 5 with the plunger rod in slightly retracted position. The extension 16 and fingers 17 are then inserted in the sockets 7 and 12 respectively. Thereupon the plunger 21 is 30 brought into engagement with the extension 19 and the bearing surfaces of the tongue and block are forced into operative engagement with each other against the tension of the spring 24 by suitable adjustment of the 35 locking nuts 35, which actuate the bell crank lever 28. The cover 36 is then secured on the box or housing, which holds the hub of the bell-crank lever securely in place and prevents interference, either malicious or 40 accidental, with the lever and its adjusting devices. If necessary, at any time, to further adjust the switch tongue, the cover 36 of the housing is removed and the locking nuts are adjusted as desired until the bearing 45 parts of the switch are brought into proper relation with each other. In case it is desired to remove the switch tongue for purposes of replacement or repair, the locking nuts are loosened so as to remove the 50 pressure between the plunger rod 21 and the extension 19 and thereupon the switch tongue may be removed. By means of this construction, an extremely broad bearing surface is provided between the tongue and 55 the heel block, thus providing a rigid tread surface and also providing against breakage or fracture of the parts. The tongue not only has a central bearing against the heel block, but also possesses lateral bearings at 60 the extreme outer edge of the tongue, which prevents tilting and also affords an additional factor of safety against lateral or vertical displacement. The spring mounted in the plunger rod also provides for automatic adjustment of the bearing surfaces to

compensate for wear of the parts without manual adjustment by means of the bell crank lever.

Although I have shown one form of construction embodying my construction, it will 70 be obvious that various changes and modifications may be made therein without departing from the spirit of the invention provided the means set forth in the following claims be employed.

I claim as my invention:—

1. In a tongue switch the combination of a switch plate comprising a heel-block having a tread surface and a curved bearing face, a tongue having its heel reversely curved to engage the bearing face of the heel-block, a bell-crank lever provided with an arm projecting outside the line of the switch, a yielding connection between the lever and switch tongue and means for securing said lever and switch tongue in adjusted position.

2. In a tongue switch the combination of a switch plate comprising a heel-block forming a tread surface and having a convexly 90 curved bearing face, a tongue having a concavely curved heel portion to engage the bearing face of the heel-block, means for holding said bearing surfaces in bearing engagement comprising a bell-crank lever a 95 yielding connection between the lever and switch tongue, and means for holding said bell-crank lever and the tongue in adjusted position.

3. In a tongue switch, the combination 100 with a switch plate comprising a heel-block, a tongue having a bearing on the heel block having a plurality of extensions engaging the switch plate beneath the flange way thereof to hold the tongue against vertical displacement and means for yieldingly holding said tongue and heel-block in engagement.

4. In a tongue switch the combination 110 with a switch plate comprising a heel-block having a convex bearing face with an undercut socket beneath said face and provided with recesses below the flange way of the switch plate, a tongue having a concavely curved bearing face engaging with the heel-block and a lip or extension engaging in said socket and with lateral extensions formed integral with the crescent ends of the tongue to engage in said recesses, a bell-crank lever 115 operatively connected with said tongue to hold said extension in position, and means for holding said lever in adjusted position.

5. In a tongue switch, the combination 125 with a switch plate provided with a heel-block having a convex bearing face, and an undercut socket beneath said face, of a tongue having a reversely curved bearing face and a lip or extension engaging in said socket, a plunger engaging said tongue to hold the bearing surfaces in engagement and 130

- a bell-crank lever operatively connected with said plunger.
6. In a tongue switch the combination with a switch plate comprising a heel-block 5 having a convexly curved bearing face centrally thereof, a bearing socket beneath said bearing face and locking sockets at the sides thereof, of a tongue having a concavely curved bearing face, a locking extension adapted to engage in said bearing socket and lateral extensions adapted to engage in said locking sockets, a plunger engaging said tongue to hold said bearing surfaces in engagement and a bell-crank lever pivoted 10 to said plunger for actuating the same.
7. In a tongue switch the combination of a switch plate having a convexly curved bearing face and a recess in front thereof, a tongue provided with a reversely curved bearing face and an extension projecting in said recess, a yielding plunger in said recess, and means for actuating said plunger comprising a bell-crank lever pivoted at one end to said plunger, and means engaging 20 the other end of said bell-crank lever to hold the same in adjusted position.
8. The combination of a switch plate having a heel block thereon provided with a convexly curved bearing face and lateral bearing surfaces, a tongue provided with a concavely curved bearing face and with lateral extensions engaging said lateral bearing surfaces, an arm secured to said tongue, a plunger provided with a central bore engaging said arm, a spring in said plunger and means for adjusting said plunger manually against the tension of the 30 spring.
9. A tongue switch comprising a switch plate having a heel-block formed integral therewith provided with a convexly curved bearing face on the top of the switch plate, lateral bearing surfaces on the bottom of said switch plate, and a central recess in 40 front of the heel-block, a tongue with bearing surfaces adapted to engage the bearing surfaces on the switch plate, a depending arm on said tongue extending into the recess, a plunger engaging said arm comprising parts movable with respect to each other, and a spring between said parts, one of said parts having a curved bearing surface adapted to engage with the bearing surface of said arm and means secured to the other 50 part of said plunger for forcing the bearing surfaces into engagement with each other.
10. A tongue switch comprising a switch plate having a heel-block with a bearing face thereon above the switch plate and lateral bearing surfaces below the switch plate, a tongue provided with a plurality of bearing surfaces adapted to engage the bearing surfaces on the switch plate, a recess in the switch plate in front of said bearing surfaces, an arm on the tongue extending 60
- into said recess, a plunger movably mounted in the recess adapted to engage said arm on the tongue, a bell-crank lever operatively connected with said plunger for actuating the same and having one of its arms provided with a slot, and means for holding said lever in its adjusted position comprising a bolt having an eye, a pin passing into said eye, a guide for said pin permitting movement of the bolt with respect to said lever and means on said bolt to hold the lever in adjusted position.
11. In a tongue switch, the combination of a switch plate provided with lateral flanges extending into the flange way, of a switch tongue pivoted to said switch plate and provided with lateral extensions engaging under said flanges.
12. In a tongue switch, the combination of a switch plate provided with lateral flanges extending into the flange way, a heel block formed integral with said plate having a convexly curved bearing surface, a tongue having a concavely curved bearing surface engaging the bearing on the heel block, and extensions formed integral with the tongue engaging under the lateral flanges to hold the tongue against vertical displacement.
13. In a tongue switch, the combination of a switch plate comprising a heel block provided with a convexly curved bearing face and with lateral flanges extending into the flange way, of a tongue having a concavely curved heel portion engaging the heel block and provided with lateral flanges extending into the flange way, said flanges being extended rearwardly to form fingers engaging under the flanges on the heel block.
14. In a tongue switch, the combination with a heel block having a curved bearing face and with lateral extensions projecting into the flange way that are provided with bearing surfaces on their bottoms, of a tongue having a curved bearing portion to engage the heel block and having laterally extending flanges, said flanges being extended rearwardly and downwardly to engage the bearing surfaces on the switch plate flanges.
15. In a tongue switch, the combination of a switch plate provided with a heel block having a curved bearing surface, and having flanges extending into the flange way, a rod passing underneath the switch plate and below said flanges adjacent thereto to form a socket between said flanges and rod, and a tongue provided with lateral extensions, said extensions being extended rearwardly and downwardly to engage in said sockets.
16. In a tongue switch, the combination of a switch plate having a heel block provided with a bearing surface, a tongue provided with a bearing surface, and means for

holding said surfaces in engagement comprising a bell crank lever operatively engaging the tongue, a box inclosing the hub of said lever, and a cover on said box having a lip adapted to engage said hub in the cover's closed position and prevent displacement of said hub.

This specification signed and witnessed this 2nd day of January, A. D., 1913.
